United States Patent Office

Des. 189,346
Patented Nov. 29, 1960

189,346

CHAIR

Morton R. Cohen, 5490 S. South Shore Drive,
Chicago, Ill.

Filed Dec. 2, 1958, Ser. No. 53,611

Term of patent 14 years

(Cl. D15—1)

Fig. 1 is a front elevational view of a chair embodying my new design; and

Fig. 2 is a side elevational view of the same.

The dominant portions of the design are shown in full lines on the drawing.

I claim:

The ornamental design for a chair substantially as shown and described.
